UNITED STATES PATENT OFFICE.

JOHN A. BYERS, OF CHICAGO, ILLINOIS, ASSIGNOR TO JAMES B. CLOW & SONS, OF CHICAGO, ILLINOIS, A CORPORATION OF ILLINOIS.

CASTING MACHINE.

Application filed July 27, 1922. Serial No. 577,845.

To all whom it may concern:

Be it known that I, JOHN A. BYERS, a citizen of the United States, and resident of Chicago, in the county of Cook and State of Illinois, have invented a certain new and useful Improvement in Casting Machines, of which the following is a full, clear, concise, and exact description, reference being had to the accompanying drawing, forming a part 10 of this specification.

The present invention relates to machines for casting molten metal by centrifugal force against the internal surface of a rotating mold. Its principal object is the provision 15 of improved means for distributing molten metal to the surface of the rotating mold, such means being especially advantageous in connection with elongated molds.

In the drawing,—

20 Figure 1 is a side elevation partly in section of a machine embodying the invention.

Figure 2 is a detailed view of certain of the mechanism looking at the side opposite that shown in Figure 1.

25 Figure 3 is a section on the line 3—3 of Figure 2.

In the preferred form of the invention which is illustrated in the drawings and described herein, an annular casing 1, preferably of cast iron, is fixedly mounted on suitable supports 2. A tubular mold 3, which is preferably of forged steel, is rotatably mounted within the casing 1 on a plurality of anti-friction bearings 4. The mold may 30 be provided with a pulley 5 or other suitable means for rotating it.

A track 6 extends longitudinally from one end of the casing and mold and a carriage 7 is mounted to travel on the track by wheels 40 8 and 9 engaging the upper and under surfaces of the flanges of the track. A pair of standards 10 are mounted on the carriage 7 and a distributor 11 is rotatably mounted in suitable bearings in the standards 10.

45 The distributor 11 projects forwardly from the carriage 7 and in operative position is adapted to extend through the mold 3, the forward end of the distributor riding on a roller 12. When the distributor is in operative position its forward end projects beyond the forward end of the mold and this end of the distributor is formed with a filling opening 13. That portion of the distributor which lies within the mold 3 when the distributor is in operative position during the

casting operation is formed with an opening in its top extending substantially the length of the mold. One edge of this opening is formed with longitudinally separated discharge outlets or spouts 14 and the distributor on rotation is adapted to discharge longitudinally separated streams of molten metal onto the mold surface at an acute angle and in the direction of rotation thereof. In order to render the distributor rotatable it is provided with a worm gear 15 meshing with a worm 16 journaled on the carriage 7 and provided with an operating handle 17. The gear 15, however, is feathered on the distributor 11 by a key 18 so that

60 the distributor is forced to rotate with the gear but may slide longitudinally with respect thereto. A standard 19 on the carriage is formed with a cam race 20 engaged by a roller 21 projecting radially from the distributor 11. The cam race 20 is preferably 70 designed, as most clearly illustrated in Figure 2, so that by rotation of the distributor through 45 degrees it will be longitudinally retracted a certain distance and by rotation 75 through an additional 45 degrees it will be advanced the same distance to its original longitudinal position.

The distributor is preferably designed to be rotated through 90 degrees to effect its discharge of molten metal into the mold and the distance through 80 which the distributor is reciprocated longitudinally is preferably the distance between centers of two adjacent discharge outlets 14.

In operation the distributor is projected into operative filling position as illustrated in Figure 1 and is then filled through the projecting end with molten metal. The mold is then rapidly rotated. By means of 95 the handle 17 the distributor is then rotated, preferably gradually, to discharge the molten metal through the longitudinally separated discharge outlets onto the mold surface at an acute angle and in the direction 100 of rotation of the mold. At the same time the distributor is automatically reciprocated longitudinally through a limited distance. Consequently, the molten metal is evenly and quietly distributed onto the rotating 105 mold surface. The reciprocation of the distributor aids in the smooth and even distribution of the metal onto the mold surface and prolongs the life of the mold by distributing the longitudinally separated 110

streams of inflowing metal over the entire mold surface instead of allowing the respective streams always to meet the mold surface on the same circle.

5 Having thus described my invention, what I claim as new and desire to secure by Letters Patent of the United States is:—

10 1. In a casting machine, the combination of a rotary mold, a distributor adapted to extend within the mold, means for rotating the distributor, and means for causing reciprocation of the distributor longitudinally by its rotation.

15 2. In a casting machine, the combination of an elongated rotary mold, a distributor adapted to extend within the mold and provided with longitudinally separated discharge outlets, means for rotating the distributor, and means for causing reciprocation of the distributor longitudinally by its rotation.

20 3. In a casting machine, the combination of an elongated rotary mold, a distributor adapted to extend within the mold and provided with longitudinally separated discharge outlets adapted to direct molten metal onto the mold surface at an acute angle and in the direction of rotation thereof, means for rotating the distributor, and means for causing reciprocation of the distributor longitudinally by its rotation.

25 4. In a casting machine, the combination of an elongated rotary mold, a distributor adapted to extend within the mold and provided with longitudinally separated discharge outlets, means for turning the distributor on its axis to discharge molten metal therefrom, and means operable by turning of the distributor to reciprocate the distributor longitudinally approximately the distance between adjacent discharge outlets.

30 5. In a casting machine, the combination of an elongated rotary mold, a distributor adapted to extend within the mold and

provided with longitudinally separated discharge outlets, means for rotating the distributor, a roller projecting radially from the distributor, and a relatively fixed cam-way engaging the roller and formed to reciprocate the distributor. 45 50

6. In a casting machine, the combination of an elongated rotary mold, a distributor adapted to extend within the mold and provided with longitudinally separated discharge outlets, a worm gear feathered on the distributor, a worm meshing therewith, a roller projecting radially from the distributor, and a relatively fixed cam-way engaging the roller and formed to reciprocate the distributor. 55 60

7. In a casting machine, the combination of an elongated rotary mold, a longitudinally movable carriage, a distributor supported by the carriage and adapted to be projected within the mold, the distributor being provided with longitudinally separated discharge outlets, means for rotating the distributor, and means for causing reciprocation of the distributor longitudinally relatively to the carriage and mold by its rotation. 65 70

8. In a casting machine, the combination of an elongated rotary mold, a longitudinally movable carriage, a distributor supported by the carriage and adapted to be projected within the mold, the distributor being provided with longitudinally separated discharge outlets, a worm gear feathered on the distributor, a worm journaled on the carriage and meshing with the gear, a roller projecting radially from the distributor, and a cam-way fixed on the carriage and engaging the roller and formed to reciprocate the distributor. 75 80

9. In witness whereof, I hereunto subscribe my name this 24 day of July, 1922. 85

JOHN A. BYERS.
